Attorney

UNITED STATES PATENT OFFICE.

JOHN T. HUFF, OF CHICAGO, ILLINOIS.

SHELF BRACKET.

Application filed June 23, 1921. Serial No. 479,827.

To all whom it may concern:

Be it known that I, JOHN T. HUFF, a citizen of the United States, residing at Chicago, in the county of Cook and State of Illinois, have invented a new and useful Shelf Bracket, of which the following is a specification.

This invention aims to provide novel means whereby a shelf bracket may be adjusted vertically and be held securely in adjusted positions on a support.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the drawings:—

Figure 1 shows in side elevation, a device constructed in accordance with the invention; Figure 2 is a front elevation wherein parts are broken away; Figure 3 is a rear elevation; Figure 4 is a section on the line 4—4 of Figure 3; Figure 5 is a section on the line 5—5 of Figure 3; Figure 6 is a fragmental perspective showing a part of the support; and Figure 7 is a fragmental perspective showing a part of the angle member.

In carrying out the invention there is provided a support 1 in the form of a strip having apertures 2 for the reception of securing elements, whereby the support may be mounted in place on a wall or the like. Any desired number of openings 3 are formed in the support 1, the openings being tapered at their lower ends, as shown at 4. Keepers 5 outstand from the forward surface of the support 1 and extend across the tapered portions 4 of the openings 3.

An angle bracket 6 is provided, the same including an outstanding arm 7 and a depending arm 8, the arms 7 and 8 being located approximately at right angles to each

other. Loops 9 are struck from the arms 7 and 8 adjacent to the ends thereof, the loops 9 being adapted to receive the ends 10 of a brace 11. Openings 12 are formed in the arm 8 of the bracket 6 and rearwardly offset tongues 14 depend from the arm 8 at the upper ends of the openings 12. The tongues 14 are tapered to cooperate with the tapered portions 4 of the openings 3.

In practical operation, the arm 8 is placed against the support 1 the tongues 14 being disposed in the openings 3 of the support 1. Then, the bracket 6 is carried downwardly, the tongues 6 engaging behind the keepers 5. Since the openings 3 are tapered at their lower ends, and since the tongues 14 are tapered to correspond with the shape of the portions 4 of the openings 3, the wedging action will result, whereby the angle bracket will be held securely on the support 1.

I claim:—

In a device of the class described, a support having an opening, the lower portions of the side edges of the opening converging downwardly, the support being provided with a forwardly offset keeper, the upper edge of which is located in approximate alignment with the upper ends of the converging lower portions of the side edges of the opening, the keeper being joined to the support along the lower edge of the keeper and along the side edges thereof; and a bracket having a depending arm provided with an opening of less width than the support and of such width as to receive the keeper closely, the arm being supplied with a straight rearwardly offset tongue of less width than the opening in the arm and adapted to be received behind the keeper, the side edges of the tongue converging downwardly to cooperate with the downwardly converging lower portions of the side edges of the opening in the support, thereby to prevent lateral movement of the bracket on the support.

In testimony that I claim the foregoing as my own, I have hereto affixed my signature in the presence of two witnesses.

JOHN T. HUFF.
